UNITED STATES PATENT OFFICE.

EDWARD A. GUTERMANN, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A PERCOLATOR, STAND, AND LAMP.

No. 38,971.

Specification for Design.

Patented Dec. 31, 1907.

Application filed October 18, 1907. Serial No. 398,134. Term of patent 3½ years.

To all whom it may concern:

Be it known that I, EDWARD A. GUTERMANN, a citizen of the United States, residing at Meriden, New Haven county, Connecticut, have invented a new, original, and ornamental Design for a Percolator, Stand, and Lamp, of which the following is a specification, reference being had to the accompanying drawings.

My invention relates to a new, original and ornamental design for a percolator, stand and lamp shown in the accompanying drawings.

The figure is a side elevation of a percolator, stand and lamp, showing my new design.

I claim:

The ornamental design for a percolator, stand and lamp as shown.

EDWARD A. GUTERMANN.
